PORTABLE ROTARY HAMMER

Frank J. Kuenzl, Deerfield, Ill., assignor to Skil Corporation, Chicago, Ill., a corporation of Delaware

Filed Sept. 20, 1963, Ser. No. 76,653

Term of patent 14 years

(Cl. D54—14)

FIG. 1 is a perspective view of a portable rotary hammer, embodying my new design;

FIG. 2 is a slightly enlarged side elevational view thereof, the other side of the portable rotary hammer is the same as the side shown except for the inclusion of the handle and the omission of the gauge rod and cylindrical supporting sleeve;

FIG. 3 is an enlarged rear view thereof;

FIG. 4 is an enlarged front view thereof; and

FIG. 5 is an enlarged top plan view thereof.

The dominant features of my design reside in the portions shown in full lines. The handle has been fragmentarily shown in FIG. 5 for convenience of illustration.

I claim:

The ornamental design for a portable rotary hammer, substantially as shown and described.
